UNITED STATES PATENT OFFICE

WILLIAM D. BELL, OF COLUMBUS, OHIO, ASSIGNOR, BY MESNE ASSIGNMENTS, TO SURFACE COMBUSTION CORPORATION, OF TOLEDO, OHIO, A CORPORATION OF NEW YORK

GAS FIRED REVOLVING HEATER

Application filed October 29, 1930. Serial No. 492,070.

This invention relates to gas-fired revolving heat radiators and the invention consists, among other things, in the provision of a fan having a hollow hub constituting a combustion chamber whereinto combustible mixture is introduced for burning, the fan having hollow blades in communication with said chamber, the products of combustion passing through said blades for heating the same in order that the air passing between the blades may be heated. The various features of novelty and invention will more fully appear from the detailed description taken in connection with the accompanying drawings wherein the preferred form of the invention is shown.

Referring to the drawings:

- Figure 1 is a rear elevation of the apparatus of my invention;
- 20 Figure 2 is a side elevation thereof;
- Figure 3 is a section on the line 3—3 of Figure 1;
- Figure 4 is a front view of one of the blades of the fan;
- 25 Figure 5 is a top plan view of a portion of the fan looking down upon the rim showing the fan blade discharge opening;
- Figure 6 shows a modified form of driving mechanism for the fan.
- 30 In the drawings, 1 indicates a platform or base from which extends a bracket comprising a lower portion 3 and an upper portion 9 terminating in a circular flange 10. As shown in Fig. 6, a driving motor 2' may be secured to the flange 10 by bolts 11, the fan and motor shaft being indicated at 14'. As shown in Fig. 2, the driving motor 2 may be supported on the base 1 in which event the fan shaft 14 will be driven by a belt 16 trained over pulleys 15 and 17 secured respectively to the fan shaft and motor shaft 18. Referring to Fig. 2, the fan shaft is supported in a bearing 13 having a circular flange 12 secured to the flange 10 by the bolts 11.
- 40 Supported by the bracket portion 3 and by arms 48 is an annular scroll or casing comprising walls 4, 5 and 6 and inwardly extending marginal rims 7 and 8 defining between them an annular passage where-through the fan blades project, the passage

being substantially sealed by a rim plate 44 secured to the fan blades. There is, of course, sufficient clearance space 46 to permit free rotation of the fan. The casing has a side outlet 47. The fan blades are hollow as indicated at 43, the walls of the blades being indicated at 41, 42. The hub 32 of the fan is hollow to form a combustion chamber 32'. One side of the combustion chamber is partially closed by an inwardly extending wall 60 33 having a central aperture 34.

Combustible mixture is introduced into the chamber 32' by a pipe 36 having a circular flange 35 surrounded by a rim 35' which projects over the edge of the hub 32 with sufficient clearance to permit free rotation of the fan. The pipe 36 is an extension of a mixing tube 36' having the usual flaring entrance 38 controlled by an air shutter 39. Gas is discharged into the tube by a gas pipe 70 40 terminating in a jet orifice nozzle 40'. Any suitable pilot means 37 shown as a spark plug, is provided for igniting the combustible mixture. A bracket 37' secured to the annular casing forms a support for the 75 pipe 36 and parts associated therewith.

The other end of the combustion chamber 32' is closed by a head generally indicated at 20, the head having a rim 31 to which the hub 32 is secured and having a hub 19 secured to the driving shaft 14 (14' in Fig. 6). The head is preferably made in two sections 23 and 24 secured by bolts 22, the walls 21 and 25 of said sections forming between them a chamber 26 shown as divided by a partition 85 27 which is clamped between said sections. Spaced from the wall 25 by lugs 30 is a baffle plate 29.

The primary purpose of the chamber 26 in the head 20 is to prevent free transfer of 90 heat from the combustion chamber 32', the baffle 29 also functioning to that end. To facilitate the abstraction of heat from the head, provision is made for passing air therethrough into the combustion chamber 32'. 95 Thus the outer wall 21 is provided with one or more apertures 27'; the partition 27 with a central aperture 27', and the inner wall with a central aperture 28. The baffle 29 deflects the air radially from the aperture 28 and, of 100

course, serves as a shield for protecting the wall 25 from the flames of combustion within the combustion chamber 32'. For further dissipating heat absorbed by the head it is provided with fins or webs 20'. By providing the partition 27 in the chamber 26, the efficiency of the chamber as a heat insulator is materially increased. The partition is made of a good heat conductor, such as aluminum, and is extended beyond the head and provided with vanes 27^b for assisting in the dissipation of heat absorbed by the partition. It will now be readily appreciated that the air which flows through the head into the combustion chamber abstracts heat from the head and, therefore, not only assists in keeping the head cool but the air is preheated before entering the combustion chamber thereby materially increasing the efficiency of the heating unit as a whole.

The mode of operation may be briefly described as follows: The purpose of the apparatus is, of course, to heat the air passing between the fan blades when the fan is in motion. The hot gases generated in the combustion chamber 32' flow outwardly through the hollow blades of the fan thereby heating the blades. The waste gases from the blades discharge into the annular casing around the fan. The outlet 47 of the casing will be connected to an exhaust pipe for leading the gas to a suitable point of discharge.

Due to the rotation of the fan, a sub-atmospheric pressure exists in the combustion chamber 32'. Due to this fact, air will be induced to enter the mixing tube 36' independently of the inducing effect of the jet of gas from the gas nozzle 40' and consequently the resulting mixture can be made to more nearly approach the proportions required to form an explosive mixture, it being understood that as long as the velocity of the mixture in the pipe 36 is in excess of the rate of flame propagation through the mixture, back flash into the mixing tube will not occur. Such additional air as may be needed to insure complete combustion of the fuel will be furnished by the air passing through the head 20 and between the closure plate 35 and hub wall 33.

Having thus fully described my invention, what I claim as new and desire to secure by Letters Patent, is:

1. In a revolving heater, the combination of a fan having a hollow hub forming a combustion chamber and having hollow blades in communication with said chamber, means for rotating said fan including a head forming a closure for one end of said chamber, and means for introducing at least one of the constituents of combustion through said head.

2. In a revolving heater, the combination of a fan having a hollow hub forming a combustion chamber and having hollow blades in communication with said chamber, means

for rotating said fan including a head forming a closure for one end of said chamber, and means for cooling said head including a passage for the flow of air through the head into said chamber.

3. In a revolving heater, the combination of a fan having a hollow hub forming a combustion chamber and having hollow blades in communication with said chamber, means for rotating said fan including a head forming a closure for one end of said chamber, a chamber formed in said head, and means extending into said last mentioned chamber for abstracting heat therefrom.

4. In a revolving heater, the combination of a fan having a hollow hub forming a combustion chamber and having hollow blades in communication with said chamber, means for rotating said fan including a head forming a closure for one end of said chamber, a baffle carried by and spaced from the inner side of said head, and means for introducing air between the baffle and said head.

5. In a revolving heater, the combination of a fan having a hollow hub forming a combustion chamber and having hollow blades in communication with said chamber, means for rotating said fan including a head forming a closure for one end of said chamber, and means at the other end of said chamber for introducing combustible mixture thereinto.

6. In a revolving heater, the combination of a fan having a hollow hub forming a combustion chamber and having hollow blades in communication with said chamber, means for rotating said fan including a head forming a closure for one end of said chamber, a casing surrounding the fan for receiving the waste gases of combustion discharged from said blades, and means at one end of said chamber for delivering combustible mixture thereinto for burning therein.

In testimony whereof, I affix my signature.

WILLIAM D. BELL.
